UNITED STATES PATENT OFFICE.

HARVEY W. BELL, OF YONKERS, AND HAZEN L. HOYT, JR., OF GREAT NECK, NEW YORK.

FRICITION-DRIVE MECHANISM.

1,418,355.

Specification of Letters Patent. Patented June 6, 1922.

Application filed April 15, 1920. Serial No. 374,062.

To all whom it may concern:

Be it known that we, HARVEY W. BELL, residing at Yonkers, New York, and HAZEN L. HOYT, Jr., residing at Great Neck, Long Island, New York, citizens of the United States, have invented certain new and useful Improvements in Friction-Drive Mechanism, of which the following is a specification.

10 This invention relates particularly to motor vehicles such as the small locomotives employed on industrial railways.

The objects of the invention are to provide a simple and practical apparatus of this character which will stand the hard usage to which such devices are subjected and which will furnish the desired changes in speed without undue wearing of the parts, and which will also furnish at all times the 20 required certainty of drive and control of operation.

The various novel features of the invention, combinations and arrangement of parts will be disclosed in the course of the following specification which is to be read in conjunction with the accompanying drawings forming a part thereof, and wherein I have illustrated the invention embodied in a number of commercial forms.

30 Figure 1 is a part sectional side elevation of the invention as applied to a single truck locomotive, the outlines of the latter being indicated generally by broken lines.

Figure 2 is a plan view of the same with 35 the motor omitted.

Figure 3 is a vertical sectional view taken substantially on the plane of the line 3—3 of Fig. 1.

Figure 4 is a detail part sectional view of 40 the friction disc and worm gearing.

Figure 5 is a view similar to Fig. 1 showing an application of the invention to a double truck locomotive with both trucks positively driven.

45 Figure 6 is another view of a locomotive of this character showing only the front truck driven.

Figure 7 is an enlarged plan view of the 50 forward or driven truck mechanism of this last embodiment.

Like reference characters are used to designate corresponding parts throughout the several views.

In all the several forms of the invention

illustrated, there is provided a friction driving pinion or gear 10 supported in fixed bearings and arranged for frictional driving engagement with the face of the friction disc 11. The friction pinion is splined or keyed longitudinally movable on a supporting shaft 12 which is journaled in fixed bearings 13 on the supporting frame 14. This frame may constitute the main frame of the locomotive and the motor 15 which, in this instance, is an internal combustion engine, 65 is shown mounted on this frame and directly coupled at 16 to the pinion shaft 12.

The friction disc is shown as carried by a substantially vertical shaft 17 journaled in a sub-frame 18 which is movable toward and 70 away from the friction pinion for the purpose of bringing the gears in frictional engagement. For this purpose the sub-frame is shown as pivoted at 19 to the forward end of the main frame and as shifted toward and 75 away from the main frame by means of a screw shaft 20 having a bearing 21 in the main frame and having a screw connection at 22 with the rearward end of the sub-frame. This screw shaft is shown as operated by means of a suitable handle 23 disposed within the reach of the operator. 80

The friction disc is connected with the drive wheels in the first form of the invention shown by worm or spiral gearing consisting of a worm or spiral gear 24 on the disc shaft 17 meshing with a worm gear or spiral gear 25 which carries sprocket pinions 26 connected by chains 27 with sprocket gears 28 on the axles of the car. 90

With this construction it is possible without disturbing the main bearings and without disturbing the positive drive connections to couple and uncouple the friction gearing by simply turning the handle of the screw shaft. It is obvious that a comparatively slight movement of the sub-frame will carry the friction gearing into and out of engagement, and by reason of the screw shaft the frictional engagement may be regulated to 100 a point where no slippage occurs and there is no binding or undue wearing of the parts.

The friction pinion is shown as shifted for the purpose of changing speed by means 105 of a fork 29 engaged with the pinion and operated by a screw shaft 30 provided with a hand wheel 31.

Another special feature of the invention is the combining of the brake mechanism with the friction disc. This is accomplished by providing the friction disc on the under side 5 thereof with a brake drum extension 32 and by mounting a brake band 33 by supports 34 on the sub-frame, said brake band being operated by the lever 35 having a suitable handle 36 disposed within easy reach of the 10 operator.

It will be apparent that by operating the three controls 23, 31, 36, the driver may couple and uncouple the gearing, effect necessary speed changes and apply or release the brakes at will.

In the double truck locomotive illustrated in Fig. 5, power is transmitted to both trucks by means of a bevel pinion 40 on the lower end of the disc shaft meshing with a 20 bevel gear 41 on the longitudinally disposed shaft 42 journaled in the gear casing 43, which is supported on the adjustable sub-frame, said shaft having coupled to its opposite ends by universal joints 44, the propeller shafts 45 which carry bevel pinions 46 in mesh with bevel gears 47 on the car axles 48. The driven car axles of the two trucks are shown as coupled to the companion axles by belts or chains 49 and pulleys or 30 gears 50.

With this construction the control is effected as before, that is by shifting the sub-frame and with it the main portion of the gearing, so as to carry the friction disc into 35 and out of engagement with the driving pinion, the flexible connections to the car axles permitting of such adjustments. In the double truck locomotives illustrated in Figs. 6 and 7, only the forward truck is 40 driven and in this construction the gear case 55 is mounted on and carried by the truck instead of being mounted on the sub-frame as in the preceding figures.

The vertical shaft of the friction disc in 45 this construction is in substantial alinement with the king bolt of the truck so that the swiveling of the truck will have no effect on the drive, and one or more universal joints 56 may be interposed in the connections 50 between the disc shaft and the gear casing to allow for the rocking movements of the truck. These joints may also include sliding connections to allow for any spring action of the locomotive carriage. The 55 gears in the gear casing 55 may be of the worm or spiral gear type first disclosed or the bevel gearing disclosed in the second form, and the connections from such gearing are shown as sprockets or pulleys 57, 60 chains or belts 58 and sprockets or pulleys 59 on the car axles 60.

The control of this form of the invention is the same as previously described, in that the friction disc which is supported below 65 the friction pinion is shifted bodily toward

and away from the pinion so as to effect the coupling and uncoupling of the driving force. This arrangement of the friction disc brings it close to the drive wheels allowing for short simple drive connections and 70 enables the over-all height of the locomotive to be kept quite low.

The mounting of the driving pinion in fixed bearings insures that said pinion will run true at all times and obviates the need 75 for any universal or flexible couplings between the motor and said driving pinion. This structure also permits of all parts being made rugged and strong, and in such simple form that they are not liable to get out of 80 order.

While we have illustrated only a few of the possible forms in which the invention may be embodied, we wish it understood that modifications and changes may be made 85 in the structure without departure from the true spirit and scope of the invention as defined in the appended claims.

What we claim is:

1. In apparatus of the character described, 90 a frame, a driving pinion journaled in fixed bearings on said frame but adjustable longitudinally of its axis, a second frame, a friction disc journaled in the second frame and rotating on an axis substantially at right angles to the axis of the pinion, and means for shifting said second frame and friction disc bodily toward and away from the friction pinion.

2. An apparatus of the character described, 100 comprising a frame, a horizontal shaft journaled in fixed bearings on said frame, a driving pinion longitudinally movable on said shaft, a second frame, a friction disc journaled in bearings on said second frame 105 and on a substantially vertical axis below the friction pinion, and means for bodily adjusting said second frame and friction disc toward and away from the friction pinion.

3. An apparatus of the character described, 110 comprising a frame, a horizontal shaft journaled in fixed bearings on said frame, a driving pinion longitudinally movable on said shaft, a second frame, a friction disc journaled in bearings on the second frame and 115 on a substantially vertical axis below the friction pinion, means for bodily adjusting said second frame and friction disc toward and away from the friction pinion, supporting wheels for the apparatus, and gearing 120 from the friction disc to said supporting wheels including flexible connections allowing for the bodily adjustment of the friction disc.

4. In apparatus of the character described, 125 a driving pinion journaled in fixed bearings but adjustable longitudinally of its axis, a friction disc rotating on an axis substantially at right angles to the axis of the pinion, means for shifting said friction disc bodily 130

toward and away from the friction pinion, and a brake for the friction disc bodily adjustable therewith.

5. In apparatus of the character described, a driving pinion journaled in fixed bearings but adjustable longitudinally of its axis, a friction disc rotating on an axis substantially at right angles to the axis of the pinion, means for shifting said friction disc bodily 10 toward and away from the friction pinion, a brake for the friction disc bodily adjustable therewith, and controlling means for the friction pinion, friction disc and brake operative irrespective of the variously adjusted 15 conditions of such parts.

6. A locomotive comprising supporting wheels, a main frame carried thereby, a sub-frame adjustably mounted on the main frame, a driving pinion journaled in fixed 20 bearings on the main frame, a driven disc for engagement by said pinion journaled in the sub-frame, means for shifting the sub-frame, and flexible drive gearing from the driven disc to the supporting wheels.

25 7. A locomotive comprising supporting wheels, a main frame carried thereby, a sub-frame adjustably mounted on the main frame, a driving pinion journaled in fixed bearings on the main frame, a driven disc 30 for engagement with said pinion journaled in the sub-frame, means for shifting the sub-frame, and flexible drive gearing from the driven disc to the supporting wheels and including gears supported on and movable 35 with the sub-frame.

8. In a motor driven vehicle, a main frame, a motor mounted thereon, a shaft driven by said motor and journaled in fixed bearings on said main frame, a pinion shiftable longitudinally on said shaft, a subframe pivotally connected with the main frame, means for swinging said sub-frame toward and away from the main frame, a friction disc carried by a shaft journaled substantially vertically 45 in the sub-frame beneath the friction pinion, a gear on the lower end of said shaft, a gear journaled in the sub-frame and engaged by said last mentioned gear, supporting wheels for the vehicle, and flexible driving connections from the last gear to said supporting wheels.

9. In a motor driven vehicle, a main frame, a motor mounted thereon, a shaft driven by said motor and journaled in fixed 55 bearings on said main frame, a pinion shiftable longitudinally on said shaft, a sub-frame pivotally connected with the main frame, means for swinging said sub-frame toward and away from the main frame, a friction disc carried by a shaft journaled substantially vertically in the sub-frame beneath the friction pinion, a gear on the

lower end of said shaft, a gear journaled in the sub-frame and engaged by said last mentioned gear, supporting wheels for the vehicle, flexible driving connections from the last gear to said supporting wheels, a brake drum carried by the friction disc, and a 65 brake band supported on the sub-frame and movable therewith.

10. In apparatus of the character described, a friction pinion journaled in fixed bearings and adjustable longitudinally of its axis, a friction disc journaled on an axis substantially at right angles to the axis of 70 the pinion and provided with a brake drum, means for bodily shifting the friction disc toward and away from the pinion, and a brake band supported for engagement with the brake drum irrespective of the bodily 75 adjustment of the friction disc.

11. In apparatus of the character described, a friction pinion journaled in fixed bearings and adjustable longitudinally of its axis, a friction disc journaled on an axis 85 substantially at right angles to the axis of the pinion and provided with a brake drum, means for bodily shifting the friction disc toward and away from the pinion, and a 90 brake drum engaging member bodily adjustable with the friction disc.

12. Apparatus of the character described comprising a main frame, a shaft journaled in fixed bearings in said main frame, a longitudinally movable drive pinion keyed on 95 said shaft, a sub-frame pivoted at one end to the main frame, a screw engaged with the opposite end of the sub-frame for shifting the same with respect to the main frame, a driven disc journaled on the sub-frame 100 intermediate the pivoted and screw actuated ends thereof and adjustable with said sub-frame into and out of engagement with the drive pinion.

13. Apparatus of the character described 105 comprising a main frame, a shaft journaled in fixed bearings on said main frame, a longitudinally movable drive pinion keyed on said shaft, a sub-frame pivoted at one end to the main frame, a screw engaged with 110 the opposite end of the sub-frame for shifting the same with respect to the main frame, a driven disc journaled on the sub-frame intermediate the pivoted and screw actuated ends thereof and adjustable with said sub-frame into and out of engagement with the drive pinion, supporting wheels, and flexible 115 gearing from the driven disc to said supporting wheels.

In witness whereof, we have hereunto set 120 our hands this 10th day of April, 1920.

HARVEY W. BELL.
HAZEN L. HOYT, JR.
